PAGE 2

FIG. 6

FIG. 7

FIG. 1 is a side elevational view of a hydraulic boom unit embodying the present invention;

FIG. 2 is a view looking at the right-hand side of the hydraulic boom unit shown in FIG. 1;

FIG. 3 is a view looking at the left-hand side of the hydraulic boom unit shown in FIG. 1;

FIG. 4 is a view looking at the top of the unit shown in FIG. 1;

FIG. 5 is a side elevational view of the hydraulic boom unit shown in FIG. 1 in extended position;

FIG. 6 is a view looking at the top of the hydraulic boom unit shown in FIG. 5;

FIG. 7 is a view looking at the hydraulic boom unit of FIG. 5 from the right-hand side; and

FIG. 8 is a perspective view of the boom unit shown in FIG. 1.

What I claim is:

The ornamental design for a hydraulic boom unit, substantially as shown and described.
